United States Patent Office

Des. 178,971
Patented Oct. 16, 1956

178,971

DOOR KNOCKER

Clement Pasquarella, Ridgefield, Conn.

Application October 18, 1955, Serial No. 38,428

Term of patent 14 years

(Cl. D10—7)

Fig. 1

Fig. 2 is a side elevational view of the said door knocker.

I claim:

The ornamental design for a door knocker, as shown.
